06-381

E

XP D 6,236

DESIGN.

—
D. DENYVEN.

Furniture.

No. 6,236.

Patented Nov. 5, 1872.

Witnesses,
D. Denyven
H. J. Bambridge

Inventor,
David Denyven.

UNITED STATES PATENT OFFICE.

DAVID DENYVEN, OF CAMBRIDGEPORT, MASSACHUSETTS.

DESIGN FOR FURNITURE.

Specification forming part of Design No. 6,236, dated November 5, 1872.

To all whom it may concern:

Be it known that I, DAVID DENYVEN, of Cambridgeport, in the county of Middlesex and State of Massachusetts, have invented and produced a new Design for Furniture, of which the following is a full, clear, and exact description, reference being had to the accompanying photograph making part of this specification.

This design consists of a head or medallion sunk into the back of a chair, sofa, or other article of furniture, thus giving it an exceedingly ornamental and unique appearance, while the head or medallion is also prevented from hurting the back of a person leaning against it. My invention also consists in an ornamental design for the upper portion of the back of a chair or sofa.

In the photograph, each piece of furniture is provided, at the center of the upper portion of its back, with a head or medallion, b, which is sunk in a cavity, c, so as not to project beyond the surface of the surrounding portion d, the effect being unique and ornamental, while no uncomfortable projection is left for the back of a person to lean against.

The above-described sunken head or medallion may be applied at any desired point or points to articles of furniture of various forms.

The portion d, which surrounds the head or medallion b, is carved or ornamented with beading e on its lower side, and is provided on its top with a knob f. On each side is a projection, g, which rests on the top of the back of the chair or sofa. On each side of the portion d is a raised panel, h.

Claim.

What I claim as my invention, and desire to secure by Letters Patent, is—

1. The design for furniture, consisting of a sunken head or medallion, substantially as herein shown and described.

2. I also claim the design for the upper portion of the back of a chair or sofa, substantially as herein shown and described.

Witness my hand this 28th day of August, A. D. 1872.

DAVID DENYVEN.

In presence of—

P. E. TESCHEMACHER,
W. J. CAMBRIDGE.